UNITED STATES PATENT OFFICE

MAX ROTTER, OF MILWAUKEE, WISCONSIN, ASSIGNOR TO BUSCH-SULZER BROS.-
DIESEL ENGINE COMPANY, OF ST. LOUIS, MISSOURI, A CORPORATION OF MISSOURI

REVERSIBLE COMBUSTION ENGINE

Application filed August 28, 1926. Serial No. 132,111.

In reversing internal combustion engines dangerously high pressures may be developed in the cylinders through the premature readmission of the fuel. The object of my invention is to prevent or guard against the operation of the engine in such a way as to develop such dangerous pressures. The invention relates particularly to air-started marine engines of the Diesel type.

10 The accompanying drawings illustrate two forms of the invention. Fig. 1 shows generally the invention applied to a ship, and specifically a form of the invention working directly on the engine operating handle. 15 Figs. 2 and 3 are enlarged details of mechanism of Fig. 1 showing the parts in different positions. Fig. 4 is a diagrammatic elevation, partly in section, of a form of the invention working on the engine fuel pump, the 20 parts being shown in engine "running" position. Fig. 5 is a perspective of a detail of Fig. 4. Fig. 6 is a plan view of a portion of the mechanism of Fig. 4. Fig. 7 is an elevation of the mechanism adjacent the control shaft of Fig. 4, looking at right angles to the latter figure. Fig. 8 is a reproduction of a portion of Fig. 4 to show the parts in neutral or "stop" position.

Referring first to the apparatus illustrated 30 in Figs. 1 to 3: In the vessel partly outlined at 1, the multicylinder propelling engine 2 may be assumed to be of any suitable design of the general type referred to; it drives the propeller 3 through the shaft 4 in the usual 35 way. Much of the valve gearing and various of the usual engine auxiliaries and accessories are omitted from the drawing for clarity. The engine control mechanism or device whereby the operator controls or restrains 40 the supply of fuel to the engine at will, and the reversing mechanism, are represented solely by the operating and reversing handles 7 and 8 thereof. It will be understood that the control mechanism or device includes suitable 45 gearing connecting the operating handle 7 to the fuel supply system of the engine so that by moving the handle 7 the operator restrains the supply of fuel or permits fuel to pass freely, or more freely, to the engine 50 cylinders as required; and likewise gearing

connected to handle 8 resets the engine for reverse running when this handle is moved. The cam shaft for operating the valves is marked 9. The latter is positively driven by the vertical lay shaft 10 directly connected 55 to the crank shaft in the customary manner. The nature of the omitted parts is a matter of indifference to the invention as is also the particular kind of mechanism represented by the handles 7 and 8 and the manner in 60 which they perform their functions. These handles are shown as levers in Figs. 1 and 2, the operating lever 7 having the customary three positions of "air starting", "stop" and "running", arranged in that order, and the reversing lever the usual "ahead" and "astern" 65 positions. The operating lever 7 is both a part of the starting air mechanism of the engine and a part of the fuel supplying and restraining mechanism; in the "air starting" 70 position of the operating lever, compressed air alone is admitted to start the engine; while in the normal operating or "running" position, the compressed starting air is cut off and fuel is supplied to the cylinders in controlled 75 amount to continue the operation, and in "stop" neither fuel nor compressed air is supplied and if the lever is left in this position the engine will come to rest. The reversing 80 lever 8 so adjusts the valve gearing that, according to its position, the cam shaft actuates the respective valves at the proper times to rotate the crank shaft in either the forward or the backward direction. The control levers may be assumed to be interlocked in any suitable or usual manner so as to prevent the actuation of the reversing lever except when the operating lever is in its "stop" position, and also to prevent the movement of the operating lever to either side of "stop" except 85 when the reversing lever is in its "ahead" or "astern" position, this being according to customary and usual practice. After the reversing lever has been thrown, the operating lever may then be moved from "stop" to "air starting" and compressed air thereby admitted either to assist in stopping the engine or to propel it. When making a reversal, however, the operator, either through carelessness 90 or because the enclosed construction prevents 95 100

inspection of the rotating engine parts, may return the operating handle to "running" while the machine is still rotating in the original direction; that is to say, after he has thrown the reversing lever, but before the engine has stopped, he may readmit the fuel. This is particularly likely to happen on ship board where the force of the water on the propeller as the ship continues to drift in the original direction, is sufficient to cause the engine shaft to continue to rotate in the original direction even against the pressure of the starting air. If under such circumstances, the operating lever is moved to "running", ignition of the fuel takes place during the inward strokes of the pistons and dangerous pressures develop in the cylinders. By the present invention the engine must come substantially to a full stop before fuel can be readmitted.

As shown, the operating lever 7 is arranged to move between the fixed bars or guides 13 and 14 and these latter are perforated for the reception of two stop pins 15 and 16 that project from a sliding frame 17 and are adapted to be extended alternately into the path of the operating lever according as the frame is moved to the right or left and so form an obstruction to said lever located intermediate its "running" and "stop" positions (see Fig. 3). In the neutral or mid-position of the frame 17 neither pin obstructs the operating lever which may then pass between them (Fig. 2). The legs 19 and 20 of the sliding frame 17 are engaged in circumferential end grooves in a sleeve 21 that is mounted to slide on the cam shaft 9 and is externally threaded. The nut 22 on this sleeve screw carries a stud 23 engaged with the forked end of a lever 24 pivoted to a stationary part of the engine and connected through the link 25 to the reversing lever 8; through this connection the shifting of the reversing lever to its "astern" setting slides the sleeve screw on the cam shaft and thereby moves the frame 17 to the right (Fig. 3). This projects stop pin 16 into the path of the operating lever 7 between its "stop" and "running" positions as indicated. Similarly, turning the reversing lever to "ahead" moves the sleeve and frame to the left and projects the opposite stop finger 15 into the path of the operating lever. The opposite ends of the screw sleeve are provided also with oppositely directed ratchet clutch teeth, each end being adapted to engage and be driven by complementary ratchet clutch teeth formed on the adjacent clutch member 31 or 32, which latter are splined to the cam shaft and urged toward the screw sleeve by helical springs 35 and 36 and against the fixed stop collars 37 and 38. These collars are so located that the sleeve screw when occupying a middle position is out of engagement with both said sliding clutch members. When the

connections 24 and 25 with the reversing lever have moved the screw sleeve into engagement with either clutch member however, the sleeve screw will be rotated thereby provided the rotation of the cam shaft conforms to the facing of the ratchet teeth. A guide 43 fixed to a stationary part of the engine and projecting into a slot in the nut 22 parallel with the cam shaft axis, holds the nut against rotation while permitting it to slide endwise.

The operation of the apparatus of Figs. 1 to 3 is as follows: In normal running, whether "ahead" or "astern", the sleeve-screw and stop pins occupy the neutral position of Fig. 2. The operating lever is therefore free to be moved back and forth as required to control of the engine for one direction of running. To reverse the engine, assuming it to be running "ahead" or with the cam shaft rotating in the direction of the arrow 42 and in which case the nut 22 will be on the left hand end of the sleeve screw as shown in Fig. 2, the operating lever 7 is first moved to "stop", thus cutting off the fuel; the reversing lever 8 is then shifted to reverse or "astern". This movement slides the sleeve screw 21 into contact with the clutch 31 at the right and enters the stop pin 16 back of the operating lever so as to block its movement to "running" or fuel-supplying position. So long as the forward drift of the ship keeps the engine shaft turning in the forward direction, and correspondingly the cam shaft continues to turn in the direction of the arrow 42, the stop pin 16 remains held in this blocking out position, the ratchet clutch teeth 31 simply riding over the complementary teeth on the sleeve with no other effect than the compression of the spring 35. The operating handle 7 can now be moved to "air starting" position and the engine thereby started in reverse and at any time the operating handle can be moved back as far as the stop position, but the stop pin 16 prevents its movement beyond this point to the fuel-supply "running" position so long as the sleeve screw remains in contact with the clutch 31. When ultimately the compressed air has reversed the direction of the cam shaft rotation however, and thereby caused the cam shaft to rotate in the direction of the arrow 41 (Fig. 3), the teeth of the clutch 31 will lock with the teeth of the sleeve screw (Fig. 3), turn the latter in the nut 22, and thus cause the sleeve screw 21 to travel to the left until its teeth clear the teeth 31. At this point the sleeve screw will have reached its neutral position of Fig. 2 again and the stop pin 16 be withdrawn from the path of the operating lever. Fuel can now be admitted and the operation of the engine on fuel begun. The nut 22 is now at the right hand end of the sleeve screw of course; hence it will be apparent that to reverse the engine again, that is to say, to cause it to drive "ahead" again, in the direction of

the arrow 42, the opposite shifting of the reversing lever 8 to "ahead" (which can be done only when the operating lever 7 is in "stop" position) will move the sleeve screw 21 to the left into engagement with clutch 32 and hold the stop pin 15 back of the operating lever until the rotation of the cam shaft 9 rotates in the "ahead" direction of arrow 42 and then causes clutch 32 to return the sleeve screw and frame to neutral as before and all the parts to the positions of Fig. 2.

The amount of turning necessary to accomplish this result in each instance, that is to say, the number of revolutions the engine must make in the new direction in order to release the operating lever, is predetermined by the pitch of the threads on the sleeve screw or by the depth of the ratchet teeth. Obviously the clutches and sleeve screw may be applied to any other shaft that is rotated with the engine crank shaft in reversing, rather than to the cam shaft as shown, and indeed the releasing function of these parts may be accomplished by other mechanisms under the control of driven parts of the engine. In no way does the mechanism described interfere with maneuvering, that is to say, the engine may be stopped at any stage of reversing, and at any stage prior to actual reversing the reversing operation may be discontinued and the engine operation resumed in its original direction as though the mechanism of the invention were not present.

It will now be understood that the principle of my invention resides in delaying the return to fuel operation, in reversing, until the engine is quite or substantially stopped, and preferably until after the rotation of the engine has been started again in the new direction. The mechanism described requires an invariable sequence in reversing; the preferred and usual coincident interlocking of the operating handle and reversing handle assures the discontinuance of the fuel supply prior to the actuation of the lock and thereby eliminates possible careless locking of the fuel mechanism in fuel supplying position, and after fuel operation has been stopped it can be resumed again (assuming the reversing is persisted in) only after the engine has actually begun its rotations in the reverse direction.

Referring now to Figs. 4 to 8 which illustrate apparatus embodying the same principles, but an apparatus in which such control is exercised on the fuel supply system that no fuel is delivered to the engine cylinders until after the reversal of the engine is completed. This leaves the operator free to move the operating handle to any position at any time, except of course as it may be interlocked with the reversing mechanism. The operating handle is again designated 7 and the reversing handle (in this case a hand wheel or attached to a hand wheel) is designated

8. The fuel pump indicated at 59 is of the type illustrated and described in the U. S. patent to Hawkes, No. 1,341,640, June 1, 1920; the suction valves are indicated at 51, pumping plungers at 52, outlet valves at 53 and the delivery pipes (leading the fuel to the engine injection valves), at 54. The suction valves 51 are arranged to be opened by a reciprocating member 55 which strikes bell crank levers 56 (the lower end of only one of these is shown) and thereby depresses

the upper arms 57 of the bell cranks which carry cross members 58 having pins 59 to depress the suction valves as will be understood. The bell crank levers 56—57 turn on eccentrics 60 attached to the shafts 61, so that the length of the valve-open periods can be changed by rocking the shafts 61; thereby the amount of fuel supplied in the engine can be controlled in the manner described in the Hawkes patent. Control can be exercised from a number of stations substantially in the manners described in the patent, among others by the operating handle 7 which is fixed to the control shaft 64. For the purposes of this description, the crank arms 65 and 66 may be regarded as fixed to the shafts 61 so that as the crank 65 is turned counter clockwise (Fig. 4) and crank 66 clockwise the suction valves 51 are held open for progressively longer periods and in their limit positions do not close at all; in the limit positions of the cranks 65 and 66 therefore the reciprocation of the plunger 52 simply causes the fuel to surge back and forth around the suction valves and none is delivered to the engine cylinders. Links 67 and 68 connect the cranks 65 and 66 respectively to the operating handle 7 in the manner later described. While I have illustrated the Hawkes patented type of fuel pump it will be understood that my invention is not limited to this type of pump.

The point I wish principally to illustrate is a fuel supplying mechanism which ceases to deliver fuel to the engine as the links 67 and 68, for example, dictate; action on the suction valves of the fuel pump so that these valves are held open throughout the entire stroke of the pump plungers when the links 67 and 68 or other appropriate mechanism is called into action, is a preferred manner of doing this.

As in the construction of Figs. 1 to 3, I also use here an externally threaded or screw sleeve 69 mounted loosely on the engine cam shaft 9 or on some other shaft connected to the engine crank shaft to rotate "ahead" or "astern" in accordance with the rotation of the engine crank shaft. Also as before, this screw sleeve is provided at its two ends with oppositely facing clutch teeth to engage with correspondingly facing clutch teeth on clutch members 70 and 71 which are keyed to rotate with the shaft 9 by means of the pins 72 extending into axially aligned slots in the clutch

members 70 and 71, while the latter respectively are pressed toward the screw sleeve by springs 73 coacting against collars 74 pinned to the shaft. Also as before a nut 78, generally corresponding in function to the nut 22 of Figs. 2 and 3, is held against rotation and slides the threaded sleeve to the right and left of its mid position, in which position it engages neither of the clutches. 5

10 In the present instance however, the nut 78 is moved to one side or the other by means of a crank 79 having a cam slot 80 (see Fig. 5) to contain a roller 81 attached to the nut 78 as shown in Fig. 6; the crank 79 is carried 15 by a shaft 82 which is partially rotated in either direction by the reversing gear through the crank 83, link 84, and sector and worm 84 and 85, as will be understood from Fig. 4.

The movement of the screw sleeve 69 axially 20 on the shaft 9 controls the return of the links 67 and 68 leading to the fuel pump after these have been actuated at the beginning of the reversal operation to open the suction valves 51 to discontinue fuel supply. The sleeve 69 25 is provided with a circumferential slot 88, adjacent to which is a fixed frame 89 carrying two pawls 90 and 91 which can enter the slot 88 under the pull of their springs 92 when the screw sleeve 69 is in its mid position (Figs. 4 30 and 6); in both end positions of the sleeve however the pawls can rest only on elevated surfaces on the sleeve at the sides of the slot. A link 93 connects the pawl 90 to a crank 94 projecting from a sleeve 95 mounted loosely 35 on the control shaft 64 and also carrying a crank 96 connected to the link 68; similarly a link 97 connects the pawl 91 to a crank 98 extending from a sleeve 99 loosely mounted on a short shaft 100 below the control shaft 40 64, while a crank 101 connects this sleeve 99 to the link 67. Bearings to support shafts 64 and 100 are indicated at 102, these bearings being carried by the standard 103. The shaft 100 is rocked along with the control shaft 64 45 by means of the link 106 connected to the crank arms 107 and 108 respectively fixed to the shafts 64 and 100. Attached to the shafts 64 and 100 respectively and respectively adjacent the cranks 94 and 98, are two 50 cranks 110 and 111, the crank 110 having its end bent under the crank 94 while the crank 111 has its end bent above the crank 98. By reason of these cranks 110 and 111 therefore, movement of the operating handle 7 to "stop" 55 position causes the sleeves 95 and 99 to be turned in such direction as to actuate the links 67 and 68 to cause the suction valves 51 to be held open and thus discontinue the feeding of fuel to the engine, and at the same time activate the links 93 and 97 to lift the ends of the pawls 90 and 91 out of the slot 88 in the screw sleeve (see Fig. 8).

The operation of the mechanism of Figs. 4 to 8 is as follows: The engine running either 60 "ahead" or "astern", the mechanism is in the

position of Fig. 4; the suction valves 51 of the fuel pump are reciprocating regularly of course, and the fuel supply may be varied by the control handle 7 acting, for example, on the links 67 and 68 through the bent cranks 110 and 111, the pawl springs 92 returning the links 67 and 68 as and when released by the cranks 110 and 111. To reverse the engine, the operating handle 7 is first moved to "stop" position; as before it may be assumed that the operating handle 7 and reversing handle or hand wheel 8 have the usual interlocking connections to prevent the operation of the reversing mechanism except when the operating handle 7 is in the "stop" position; on the other hand it will be observed that the pawls 90 and 91 will prevent the actuation of the reversing mechanism except when the operating handle 7 is at "stop" or "air starting". With the operating handle 7 70 in "stop" position therefore and the pawls 90 and 91 withdrawn from slot 88, the reversing handle 8 is actuated in the proper manner and among other things this rocks the shaft 82 thereby causing the cam-crank 79 to shift the screw sleeve 69 endwise (to the left, assuming the parts to be initially in the position of Fig. 6) and displaces the slot 88 from underneath the pawls. The continued rotation of the engine and shaft 9 in the original direction for a while simply causes the clutch member 70 (or 71) to slide on the shaft 9 as its clutch teeth slip over the adjacent clutch teeth of the screw sleeve 69. After the engine stops and reverses however, being air 75 started in the new direction, the teeth on clutch member 70 engage with the teeth of the sleeve screw 69 and screws the sleeve screw through the nut 78 until the screw sleeve 69 80 reaches its midposition and the engaged clutch teeth disengage. The operating handle 7 may now be returned to "running" position, or it may previously have been returned to "running" position; in the latter event 85 however, the pawls 90 and 91 dropped down on the elevated surface of the screw sleeve 69 at the side of the groove 88, which surface is of such height that it holds the ends of the pawls 90 and 91 so far elevated that the links 67 and 68 hold the suction valves 51 open. While therefore the operating handle 7 can 90 be returned to "running" position prior to the starting of the engine in the reverse direction, it is apparent that no fuel is resupplied to the engine until after the engine has made the appropriate number of revolutions in the new direction and the screw sleeve 69 returned to its original midposition. When this has 95 happened the pawls 90 and 91 can enter the circumferential slot 88 and accordingly fuel operation is or can be resumed.

It will be understood that while I have thus 100 illustrated and described two forms which my invention may assume, my invention is not 105

limited thereto except as appears hereinafter in the claims.

I claim:

1. In an internal combustion engine including engine reversing mechanism and a device for controlling the supply of fuel to the engine, means interlocking said device and the engine reversing mechanism to prevent the actuation of the reversing mechanism to 10 reverse position until the said device is actuated to restrain the supply of fuel to the engine, a locking member to lock said device in a position in which the supply of fuel to the engine is restrained, connecting means 15 between said locking member and said reversing mechanism through which the locking member is moved to locking position on setting said reversing mechanism for reversal, and connecting means between the crank shaft and said locking member to cause the movement of said locking member to unlocked position.
2. In an internal combustion engine, the combination of the engine crank shaft, engine reversing mechanism, a device for restraining the supply of fuel to the engine, said device being interlocked with the engine reversing mechanism to prevent actuation of the reversing mechanism to engine reversing 25 position prior to the imposing of restraint on the supply of fuel, and means driven by the engine crank shaft after reversal to release restraint on the supply of fuel to the engine.
3. In an internal combustion engine having a reversing mechanism, a device to prevent the supply of fuel to the engine, said device being interlocked with the reversing mechanism to prevent the supply of fuel to 30 the engine after the reversing mechanism has been actuated to engine reversing position, a shaft rotating with the engine crank shaft, and a threaded member driven by said shaft in coaction with its threads after reversal and controlling said device to permit the supply 35 of fuel.
4. In an internal combustion engine including engine reversing mechanism, a device for restraining the supply of fuel to the engine, and connection means from said device to the reversing mechanism and the engine crank shaft through which the reversing mechanism acts to impose restraint on the supply of fuel to the engine and the 40 engine crank shaft acts to release restraint on the supply of fuel to the engine.
5. In an internal combustion engine including engine reversing mechanism and a device for controlling the supply of fuel to the engine, a locking member to lock said device in a position in which the supply of fuel to the engine is restrained, connecting means 45 between said locking member and said reversing mechanism through which the locking member is moved to locking position on

setting said reversing mechanism for reversal, and connecting means between the crank shaft and said locking member to cause the movement of said locking member to unlocked position.

6. In an internal combustion engine, the combination of the engine crank shaft, engine reversing mechanism, a device actuated by the reversing mechanism to maintain restraint on the supply of fuel to the engine after the reversing mechanism has been actuated to engine-reversing position, and means driven by the engine crank shaft after reversal controlling the release of restraint on the supply of fuel to the engine.

7. In an internal combustion engine, a device for restraining the supply of fuel to the engine, and a connection between said device and the engine crank shaft through which the crank shaft acts on said device to relieve restraint on the supply of fuel to the engine.

8. In an internal combustion engine, a device to prevent the supply of fuel to the engine, a shaft rotating with the engine crank shaft, and a threaded member driven by said shaft in coaction with its threads to actuate said device.

9. In an internal combustion engine, the combination of means to prevent the supply of fuel to the engine, a shaft rotating with the engine crank shaft, a threaded sleeve slidable axially on said shaft and arranged in its two extreme positions to be rotated by the shaft, said sleeve being so related to said means as to prevent the supply of fuel to the engine when in its two extreme positions and permit the supply of fuel when in its mid-position, a member engaging with the threads of the sleeve so that the sleeve is moved axially as it is rotated, and a reversing mechanism for the engine interlocked with the sliding of the sleeve axially.

10. In an internal combustion engine, the combination of means to prevent the supply of fuel to the engine, a shaft rotating with the engine crank shaft, an externally threaded sleeve slidable on said shaft and having teeth facing in opposite directions on its two ends, said sleeve being so related to said means as to prevent the supply of fuel to the engine when in its two extreme positions and permit the supply of fuel when in its midposition, clutch members rotating with the shaft at the two ends of the sleeve, said clutch members being movable away from the sleeve and having corresponding oppositely faced teeth to engage the teeth on the sleeve to rotate the sleeve when in either of its two extreme positions, a nut on the sleeve, and engine reversing mechanism connected to the nut to slide the sleeve axially to its extreme positions as the reversing mechanism is actuated to reverse the engine.

11. In an internal combustion engine, the combination of its reversing gear, a device

controlling the supply of fuel and interlocked with the reversing gear, coacting nut and threaded members, one of said members being held against rotation, and means connecting the other of said members to the engine crank shaft to turn with the latter in reverse, one of said members being movable axially by such turning to cause said fuel controlling device to permit the supply of fuel.

10 In testimony whereof, I have signed this specification.

MAX ROTTER.
